UNITED STATES PATENT OFFICE.

CHARLES KNOX HARDING, OF CHICAGO, ILLINOIS.

APPARATUS FOR BURNING GAS.

1,304,042.

Specification of Letters Patent.

Patented May 20, 1919.

Application filed December 21, 1914. Serial No. 878,455.

To all whom it may concern:

Be it known that I, CHARLES KNOX HARDING, a citizen of the United States, residing in Woodlawn, city of Chicago, in the county 5 of Cook and State of Illinois, have invented certain new and useful Improvements in Apparatus for Burning Gas, of which the following is a specification.

This invention relates to improvements in 10 apparatus for burning gas, and one of the objects of the same is to provide an improved structure for producing flameless combustion, preferably by means of a diaphragm constructed of catalytic material, 15 for intercepting the flame to localize the flame of burning gaseous mixture at one side thereof, with the result that the chemical energy of the gaseous fluid will be largely converted into radiant energy, the dia- 20 phragm receiving and radiating part of the heat liberated, enables a higher intensity to be obtained and applied, than would be the case where the combustion or oxidation takes place between the gaseous elements them- 25 selves in the form of a flame, and with the further result that the flashing back to the point of mixture will be obviated, by reducing the inflammability of the gas mixture by its partial combustion in contact with the 30 oxidizing-non-igniting catalytic material before it reaches the flame.

I have discovered that a suitable and inexpensive catalytic diaphragm consists of a structure containing the oxids of the radio- 35 active elements thorium and uranium, and that such a flame intercepting diaphragm, constructed of any suitable catalytic mate- 40 rial, such as the structure described in my United States Patent No. 1,067,983, issued July 22, 1913, will produce and maintain flameless combustion when sufficiently heated, inasmuch as the diaphragm becomes incandescent through contact combustion of part of the combustible gaseous mixture and 45 gives off heat without flame.

I have discovered that a flame intercepting diaphragm to be most effective should be made of material which will produce flameless combustion, and will burn up or oxidize 50 part of the combustible or explosive mixture passing through it by contact or catalytic combustion absolutely without flame. Any suitable catalytic material known to those skilled in the art may be employed, that will 55 produce and maintain catalytic combustion. Colloidal palladium will cause catalytic

combustion of mixtures containing hydrogen and oxygen at a temperature of 40 degrees below zero; the other metals of the platinum group require higher temperatures to initially bring them into action. In my flame intercepting diaphragm it is only necessary that the flameless combustion becomes established before the passages get heated up to the igniting point of the mixture.

The diaphragm being perforated, the current of gaseous mixture passes therethrough, and when the gas is first ignited on the outlet side of the diaphragm, will burn in small jets of flame until the diaphragm is sufficiently heated, and after being heated, when the flowing current of gaseous mixture passes into contact with the diaphragm and through the perforations therethrough, a portion of the mixture will be consumed by 75 flameless combustion.

In the drawing there is shown one form of burner in the adaptation of my invention, and in which:

Figure 1 is a vertical longitudinal sec- 80 tional view of one form of the apparatus.

Fig. 2 is a vertical transverse sectional view taken on line 2—2, Fig. 1.

Fig. 3 is a top plan view of a diaphragm 85 constructed in accordance with the principles of this invention.

Fig. 4 is a perspective view of a support for the flame intercepting diaphragm.

The flame intercepting diaphragm 5 is constructed of catalytic material, such as 90 platinized earthen ware, and is preferably provided with perforations 6 therethrough, and in the form of the invention shown, this diaphragm 5 constitutes a portion of the wall of a gas passage or receiving chamber 95 7^a in a burner element 7, to form an outlet for a combustible gaseous mixture, and the diaphragm may be held in position by a suitable support 8 detachably connected with the element 7. This passage or chamber 7^a is 100 provided with an inlet 9, and connected with the element 7 is a suitable handle 10 suitably insulated therefrom by insulating material 11. This entire structure is adapted to be inserted within an element 12, which latter is to 105 be heated, and is removably held in position in any suitable manner such as by means of a projection 13 entering a socket 14 in one wall of the element 12 and an adjusting screw 15, the end of which enters a suitable socket 16 110 in another wall of the passage or chamber 7^a. The combustible gaseous mixture is sup-

plied by means of a jet 17, connected with any suitable source of supply as at 18, and the openings 19 admit the necessary amount of air to produce stoichi-o-metrical proportions, and this mixture passes to the diaphragm 5 and through the perforations 6 thereof.

These perforations in the diaphragm 5 preferably diverge or increase in size from 10 the entrance side of the diaphragm and this serves the purpose of confining and directing the flowing current of the mixture while being heated, so that the increased volume or energy of the mixture will increase the 15 forward velocity of the flowing current of the mixture, while at the same time the flame of the mixture will be localized on one side of the diaphragm.

To start the burner element, it is removed 20 from the element 12, and the gaseous mixture is admitted into the passage. The gaseous mixture passing through the perforations 6, is then ignited adjacent the exposed face of the diaphragm, and the mixture will 25 at first burn in small jets of flame until the diaphragm becomes heated sufficiently. With a diaphragm constructed of any ordinary material not having catalytic properties, the flame would propagate back through 30 the heated diaphragm to the point of mixture, but upon heating this improved diaphragm to incandescence a portion of the flowing current of the gaseous mixture passing into contact therewith and through the 35 perforations, will be consumed by flameless combustion and also have its velocity increased sufficiently to prevent flashing back of the flame.

The burner element is then placed within 40 the element 12, and it will be manifest that the radiation of the heat from this diaphragm, from the consumption of the gaseous fluid, will be effectively distributed to the element 12.

45 This element 12 is preferably provided with apertures 20, so that the products of combustion will pass therethrough.

While there has been shown and described one adaptation of the invention, it is to be 50 understood that a similar diaphragm may be employed in many ways, and therefor the drawing herewith submitted is to be considered as being merely diagrammatic.

In the claims, the term "oxidizing non- 55 igniting catalytic agent" means a catalytic agent that will induce oxidization of the gases, producing catalytic flameless combustion.

What is claimed as new is:

60 1. An apparatus for burning highly inflammable gaseous mixtures with a flame comprising the combination of a mixing chamber, means for passing a combustible mixture of gas and air therethrough, and a 65 flame intercepting diaphragm for localizing

the flame of burning gaseous mixture at one side thereof, and outside the mixing chamber, said diaphragm having preformed perforations extending therethrough from side to side for free passage of the mixture and 70 constructed of refractory material comprising such catalytic substance distributed throughout its mass as will produce flameless contact combustion of that portion of the mixture coming in contact with the sides 75 of the passageways.

2. An apparatus for burning highly inflammable gaseous mixtures with a flame comprising the combination of a mixing chamber, means for passing a combustible 80 mixture of gas and air therethrough, and a flame intercepting diaphragm for localizing the flame of burning gaseous mixture at one side thereof, said diaphragm having preformed perforations extending therethrough 85 from side to side for free passage of the mixture and constructed of refractory material comprising such catalytic substance distributed throughout its mass as will produce flameless contact combustion of that 90 portion of the mixture coming in contact with the sides of the passageways.

3. An apparatus for burning highly inflammable gaseous mixtures with a flame comprising the combination of a mixing 95 chamber, means for passing a combustible mixture of gas and air therethrough and a flame intercepting diaphragm for localizing the flame of burning gaseous mixture at one side thereof, and outside of the mixing 100 chamber, said diaphragm having preformed perforations diverging in size from the entrance side of the same, and extending therethrough from side to side for free passage of the mixture and constructed of refrac- 105 tory material comprising such catalytic substance distributed throughout its mass as will produce flameless contact combustion of that portion of the mixture coming in contact with the sides of the passageways. 110

4. An apparatus for burning highly inflammable gaseous mixtures with a flame comprising the combination of a mixing chamber, means for passing a combustible mixture of gas and air therethrough and a 115 flame intercepting diaphragm for localizing the flame of burning gaseous mixture at one side thereof, said diaphragm having preformed perforations diverging in size from the entrance side of the same, and extending 120 therethrough from side to side for free passage of the mixture and constructed of refractory material comprising such catalytic substance distributed throughout its mass as will produce flameless contact combustion of 125 that portion of the mixture coming in contact with the sides of the passageways.

5. An apparatus for burning highly inflammable gaseous mixture with a flame comprising the combination of a mixing 130

chamber, means for passing a combustible mixture of gas and air therethrough and a flame intercepting diaphragm for localizing the flame of burning gaseous mixtures at one side thereof, said diaphragm having preformed perforations extending therethrough from side to side for free passage of the mixture and constructed of refractory material comprising such radio-active catalytic substance distributed throughout its mass as will produce flameless contact combustion of that portion of the mixture coming in contact with the sides of the passageways.

6. An apparatus for burning highly inflammable gaseous mixtures with a flame comprising the combination of a mixing chamber, means for passing a combustible mixture of gas and air therethrough and a flame intercepting diaphragm for localizing the flame of burning gaseous mixture at one side thereof, said diaphragm having preformed perforations extending therethrough from side to side for free passage of the mixture and constructed of catalytic refractory material comprising thorium and uranium compounds distributed throughout its mass producing flameless contact combustion of that portion of the mixture coming in contact with the sides of the passageways.

7. An apparatus for burning highly inflammable gaseous mixtures with a flame comprising the combination of a mixing chamber, means for passing a combustible mixture of gas and air therethrough and a

flame intercepting diaphragm for localizing the flame of burning gaseous mixture at one side thereof, said diaphragm having preformed perforations diverging in size from the entrance side of the same and extending therethrough and from side to side for free passage of the mixture and constructed of catalytic material comprising thorium and uranium compounds distributed throughout its mass producing flameless contact combustion of that portion of the mixture coming in contact with the sides of the passageways.

8. A flame-intercepting diaphragm consisting of a perforated diaphragm containing within its mass an oxidizing non-igniting radio-active catalytic material, the perforations increasing in diameter from the inlet to the outlet thereof.

9. A flame-intercepting diaphragm consisting of a perforated diaphragm containing within its mass a catalytic material, said catalytic material containing thorium and uranium compounds, the perforations increasing in diameter from the inlet to the outlet thereof.

In testimony whereof I have signed my name to this specification, this 17th day of December, 1914, in the presence of two witnesses.

CHARLES KNOX HARDING.
